UNITED STATES PATENT OFFICE.

JAMES C. EVERTON, OF CHATTANOOGA, TENNESSEE.

DESIGN FOR A CHURN-STAND.

45,255.

Specification for Design.

Patented Feb. 17, 1914.

Application filed September 9, 1913. Serial No. 788,973. Term of patent 3½ years.

To all whom it may concern:

Be it known that I, JAMES C. EVERTON, a citizen of the United States, residing at Chattanooga, in the county of Hamilton and State of Tennessee, have invented a new, original, and ornamental Design for a Churn-Stand, of which the following is a specification, reference being had to the accompanying drawings, forming a part thereof.

Figure 1 is a plan view of a churn stand showing my design. Fig. 2 is a side elevation of the device.

I claim:

The ornamental design for a churn stand, as shown.

JAMES C. EVERTON.

Witnesses:

WALTER PHILLIPS,
S. R. DAVIS.
